GLASS TRANSFER MECHANISM

Ira H. Freese, Clarksburg, W. Va., assignor to
 Hazel-Atlas Glass Co., Wheeling, W. Va., a
 corporation of West Virginia

Original application November 29, 1927, Serial
 No. 236,524. Divided and this application
 March 22, 1932. Serial No. 600,539

10 Claims. (Cl. 198—26)

The invention relates generally to mechanism for transferring glassware from a forming machine to a conveyer, such as a continuously moving conveyer of a fire-finisher. The numerous novel features of this invention will appear from the detailed description, and will be defined by the appended claims.

This application is a division of my application, Serial No. 236,524, filed November 29, 1927; and the subject-matter of this divisional application relates particularly to means for depositing ware on a continuously moving conveyer, and the combination of associated elements.

Referring to the drawings:

15 Figure 1 is an end elevational view of the conveyer mechanism shown in combination with a mechanism for transferring the ware from a forming machine to a position over the conveyer.

Figure 2 is a plan view of the receiver mechanism, parts being broken away to more clearly show the construction.

Figure 3 is a transverse sectional view of the receiver mechanism, taken on line 3—3 of Figure 2.

25 Figure 4 is a detail view of one of the elements for opening the receiver.

Figure 5 is a side elevational view of the receiver mechanism, showing the receiver closed and holding a tumbler.

30 Figure 6 is a diagrammatic elevational view of the receiver mechanism, with the receiver closed, and one of the cups just coming into alignment therewith.

Figure 7 is a diagrammatic plan view of the receiver mechanism in the position shown in Figure 6.

35 Figure 8 is a diagrammatic plan view of the receiver mechanism, with the receiver closed and having received a tumbler, and a cup in alignment with the receiver; and

40 Figure 9 is a diagrammatic plan view of the receiver mechanism; the receiver having opened to deposit the article on the cup, and the cup having traveled almost free of the receiver, so that the receiver is almost ready to close again.

45 Referring particularly to Figure 1, numeral 113 indicates the mold of any desired forming machine in which the glass articles to be transferred are formed. Numeral 114 refers generally to an 50 endless conveyer, which is continuously moving, and which carries the desired number of cups 115. Numeral 116 refers generally to a transfer mechanism provided with gripper units 117, by which the tumblers or other glass articles are 55 removed from the molds of the forming machine

and transferred to a position directly over the path of the cups on the conveyer. It will be understood, of course, that any desired transfer mechanism may be employed, and the particular transfer mechanism shown in Figure 1 is neither 60 described nor claimed herein, as it is the subject matter of a separate application, Ser. No. 448,073, filed April 28, 1930, which application is a division of application Ser. No. 236,524, filed November 29, 1927.

65 The present invention relates to a guiding and delivery mechanism, referred to generally by numeral 118 on Figure 1, by which the transferred articles are deposited in the cups, which are preferably continuously moving.

70 Arranged beneath a gripper unit, at its point of delivery, is the guiding and delivery mechanism which momentarily receives the tumbler or other transferred article from the gripper unit, and then releases it and deposits it in one 75 of the cups which carries the article through a fire-finisher. This guiding mechanism is mounted on the main frame of the fire-finisher, and in the following description reference is to be had particularly to Figures 2 to 9.

75 Numeral 119 refers to a plate which is spaced above and attached to the main frame of the fire-finisher by means of brackets 120. Of course the plate is spaced above the main frame of the fire-finisher to permit the cups to pass beneath it, 80 as clearly shown in Figure 3. Two arms 121 rest on this plate 119; the arms being pivotally connected by a pin 122, and are intermittently opened and closed by mechanism to be described hereinafter. Each arm carries a half of a liner 123 which is preferably made of soft metal.

85 When these half-liners are brought together by the closing of the arms, they form a receiver, to receive the article delivered by the take-out mechanism. The half-liners are removable in 90 order that different liners may be employed to handle the different ware carried through the machine; and of course, the different liners will be shaped to suit the particular ware they are adapted to handle. In this particular instance I 100 have illustrated round tapered tumblers as the ware being handled, and consequently the liner is shown as round and tapered. The liners may be removably attached to the arms 121 by any desired means; the preferred means as illustrated 105 herein, consisting of a dovetail 124. The dovetail is preferably tapered to provide a rest for the liner. For a reason to appear hereinafter, the arms 121 are preferably dished at their forward ends, as indicated by numeral 125.

110

A lug 126 extends laterally from each arm 121, and a pin 127 projects downwardly from each lug and extends through an arcuate slot 128 in the plate 119. The lower ends of each of the pins 127 is received in an elongated slot 129 provided in the forward ends of levers 130. Each of the levers 130 has its rear end secured to, or integral with, a sleeve 131, which is pivotally mounted on a pin 132; the pins being attached to the plate 119 by nuts 133. A finger 134 is attached to or integral with the lower end of each sleeve 131, and these fingers extend inwardly to a position where they are in the path of the cups, when the receiver is closed, as clearly indicated in Figures 2, 7 and 8. The cups are preferably provided with a flange 135 to engage the fingers 134, and will be hereinafter described in detail.

For the purpose of closing the receiver I provide rods 136 which have their forward ends pivotally mounted on pins 137 carried by lugs 138 projecting inwardly from the brackets 120; the pins being preferably provided with oil holes 137'. These rods extend rearwardly and pass through suitable openings 139 provided in lugs 140 projecting from sleeves 131. The rods extend on rearwardly beyond the lugs 140, and mounted on the rods, beyond the lugs, are coil springs 141; the pressure on the springs being regulated by nuts 142 threaded on the rear ends of the rods 136. Thus when the levers 130 are swung outwardly to open the receiver, the lugs 140 will compress the springs 141 on the rods 136; the rods turning slightly about the pins 137 as pivots. When the flange 135 of a cup passes beyond the ends of fingers 134, thereby releasing them, the springs 141 will force the lugs forwardly, thereby rotating the sleeves 131 and the levers 130 carried thereby; and by means of the pin and slot connections between the levers 130 and arms 121, the receiver will be moved to closed position.

A complete cycle of operation of the receiver mechanism will now be described, reference being had to Figures 2, 3, 4 and 5. Attention is also called particularly to Figures 6, 7, 8 and 9, which illustrate in diagrammatic fashion various steps in the transfer of an article from the receiver to the cups. In Figures 6 and 7 the first cup has received its tumbler, and moved it free of the receiver, and the receiver has closed to receive the next tumbler; but the tumbler has not yet been fed to the receiver, and the second cup is not yet in alignment with the receiver. In Figure 8 the first two cups have received their tumblers, a tumbler has been fed to the receiver, the third cup is in alignment with the receiver, and the receiver will be opened by the succeeding cup, which is shown in position engaging the fingers 134. In Figure 9, the receiver has been opened, the third tumbler has been deposited in a cup, and the cup has been moved almost far enough to permit the receiver to close, which will occur when the next succeeding cup passes free of the fingers 134.

The continuous movement of an endless chain brings each cup successively beneath the receiver, and the whole mechanism is so timed that just as each cup is almost in alignment with the receiver, the grippers will be separated to deposit a tumbler or other article in the receiver. At this point the flange 135 of the next succeeding cup has come into engagement with the fingers 134; and the continued movement of the endless carrier will cause these fingers to swing outwardly, and open the receiver, whereby the article will be gently deposited in the preceding cup, while

the cup is continuously moving, and while it is exactly in alignment with the receiver. Of course, the manner in which the receiver is opened is apparent from the previous description of the construction. The outward movement of the fingers 134 causes the sleeves 131 to rotate, thereby swinging the levers 130 outwardly. These levers have pin and slot connections with the arms 121, and consequently the outward movement of the levers 130 will cause the arms 121 to swing open to open the receiver; this swinging movement of the arms being allowed by the arcuate slots 128 in the plate 119.

The receiver has thus been opened and the article has been deposited in one of the cups. The receiver is maintained open by reason of the continued engagement of the fingers 134 with the flange 135 of the next succeeding cup; and the continued travel of the endless carrier moves the cups with the article forwardly. Of course, the plate 119 is suitably cut away to permit the articles to pass from the receiver to the cups, and to be moved forwardly away from the receiver. Just as the continued movement of the carrier has moved the cup with the article far enough to be free of the receiver, the receiver is quickly closed. In the rapid operation of this mechanism it is essential that the receiver close at the instant the cup and article are clear; and to expedite the closing of the receiver, I have discarded the forward ends of the arms 121, as indicated by numeral 125. The manner of closing the receiver will be understood from the foregoing description of the operation. As the cup with the article is being carried forward the fingers 134 will ride on the flange 135 of the next succeeding cup, and just as the article passes clear of the open receiver, the next cup will pass clear of the fingers 134; thereby permitting the springs 141 to swing the levers 130 inwardly and forcing the halves of the receiver to closed position. This inward movement of the levers 130 also moves the fingers 134 inward into the path of the next cup, and this next cup comes into engagement with these fingers to force them apart just as the preceding cup is in alignment with the receiver, which has just received another article from the take-out mechanism, and thus the cycle is repeated.

It will be understood, of course, that the invention is by no means limited to the specific construction and operation of the receiver; but I have found that this device constitutes a highly efficient and most desirable means for receiving ware from the take-out mechanism and depositing it gently and accurately in the continuously moving cups. It is needless to add that all of the parts operate in the desired order and in the desired timed relation.

Obviously many changes and modifications may be made without departing from the spirit of the invention; and all such changes and modifications are intended to be included within the scope of the appended claims.

What I claim is:

1. A device for depositing glassware on continuously moving cups including two pivotally mounted arms, a half receiver carried by each arm, a lever connected with each arm, an inwardly projecting finger operatively connected with each lever, said fingers being engaged and moved outwardly by the cups.

2. A device for depositing glassware on continuously moving cups, including two pivotally mounted arms, a half receiver carried by each

- arm, two rotatably mounted sleeves, a lever, a finger and a lug carried by each sleeve, said levers being operatively connected with the said arms, the fingers normally in the path of the 5 cups, pivotally mounted rods passing through said lugs, and springs on said rods for normally maintaining the fingers in the path of the cups.
3. A device of the character described including an endless conveyer continuously travelling beneath a transfer mechanism, a receiver arranged above and closely adjacent to the continuously travelling conveyer, said receiver adapted to receive glassware from the transfer mechanism and deposit it upon the moving conveyer, and means for opening the receiver to deposit a piece of ware on the conveyer, said means being so constructed and arranged as to maintain the receiver open until the piece of ware has been carried forward through the open receiver.
4. A device of the character described including an endless conveyer continuously travelling beneath a transfer mechanism, a receiver arranged above and closely adjacent to the continuously travelling conveyer, said receiver adapted to receive glassware from the transfer mechanism, and means operated by the movement of the conveyer to open the receiver to deposit the piece of ware on the conveyer, said means being so constructed and arranged as to maintain the receiver open until the piece of ware has been carried forward through the open receiver.
5. A continuously moving conveyer, members carried by the conveyer upon which glassware is deposited, a receiver above and closely adjacent to said members, said receiver formed of separable halves, a pivotally mounted arm carrying each half, means engaged by said members to swing apart in a horizontal plane said arms and the receiver halves carried thereby, whereby the ware is gently deposited upon said members, said receiver remaining open until the ware is carried forward clear thereof.
6. A continuously moving conveyer, members carried by the conveyer upon which glassware is deposited, a receiver above and closely adjacent to said members, said receiver formed of separable halves, arms carrying said halves, means engaged by said members to move apart in a horizontal plane said arms and the receiver halves carried thereby, whereby the ware is gently de-

7. A continuously moving conveyer, members carried by the conveyer upon which glassware is deposited, a receiver above and closely adjacent to said members, said receiver formed of separable halves, arms carrying said halves, means engaged by said members to move apart in a horizontal plane said arms and the receiver halves carried thereby, whereby the ware is gently deposited upon said members, and means for closing the receiver after the ware is carried forward clear thereof.
8. A continuously moving conveyer, members carried by the conveyer upon which glassware is deposited, a receiver above and closely adjacent to said members, said receiver formed of separable halves, arms carrying said halves, means engaged by said members to move apart in a horizontal plane said arms and the receiver halves carried thereby, whereby the ware is gently deposited upon said members, and means for closing the receiver after the ware is carried forward clear thereof, the forward portions of the receiver halves being dished for the purpose described.
9. A continuously moving conveyer, cups carried by the conveyer upon which glassware is deposited, a receiver above and closely adjacent to said cups, said receiver formed of separable halves, pivotally mounted arms carrying said halves, fingers projecting into the path of said cups and operated thereby to swing the arms and receiver halves to open position, whereby the ware is gently deposited upon the cups, and means for closing the receiver after the ware is carried forward clear thereof.
10. A continuously moving conveyer, cups carried by the conveyer upon which glassware is deposited, a receiver above and closely adjacent to said cups, said receiver formed of separable halves, pivotally mounted arms carrying said halves, fingers projecting into the path of said cups and operated by each succeeding cup to swing the arms and receiver halves to open position to deposit ware in each preceding cup, and means for closing the receiver after the ware is carried forward thereof.
- IRAH. FREESE.
